DESIGN FOR A RUBBER HEEL

Albert A. Esterson, Baltimore, Md., assignor to
Cat's Paw Rubber Company, Inc., Baltimore,
Md., a corporation of Maryland

Application February 5, 1941, Serial No. 98,769

Term of patent 14 years

To all whom it may concern:

Be it known that I, Albert A. Esterson, a citizen of the United States, residing at the city of Baltimore, State of Maryland, have invented a new, original, and ornamental Design for Rubber Heel, of which the following is a specification, reference being had to the accompanying drawing, forming a part thereof.

Figure 1 is a bottom plan view of a rubber heel showing my design.

Figure 2 is a side elevation thereof, looking from the left of Figure 1, and

Figure 3 is a sectional view taken on line 3—3 of Figure 1.

I claim:

The ornamental design for a rubber heel, substantially as shown.

ALBERT A. ESTERSON.
